UNITED STATES PATENT OFFICE.

LOREN W. RAY ANDRIST, OF MANKATO, MINNESOTA.

CAMPING KIT.

Application filed November 4, 1921. Serial No. 512,854.

To all whom it may concern:

Be it known that I, LOREN W. RAY ANDRIST, a citizen of the United States, residing at Mankato, in the county of Blue Earth 5 and State of Minnesota, have invented a new and useful Camping Kit, of which the following is a specification.

This invention relates to a camping kit designed to be used primarily by automobile tourists, one of the objects of the invention being to provide a combined cupboard and table, the parts being so shaped and proportioned that the entire structure can be carried readily on the running board of 10 an automobile and can, without being removed therefrom, be opened so as to give access to the contents of the kit and also provide a table of convenient height on which food can be placed.

Another object is to provide a kit which is simple and compact in construction and provides ample storage space for food, dishes and utensils.

With the foregoing and other objects in view which will appear as the description proceeds, the invention resides in the combination and arrangement of parts and in the details of construction hereinafter described and claimed, it being understood that, within 25 the scope of what is claimed, changes in the precise embodiment of the invention shown can be made without departing from the spirit of the invention.

In the accompanying drawings the preferred form of the invention has been shown.

In said drawings

Figure 1 is a front elevation of the device opened for use.

Figure 2 is a side elevation.

Figure 3 is a section on line 3—3, Figure 1, showing the device closed.

Figure 4 is a perspective view of a portion of one of the braces.

Figure 5 is a plan view of the bottom of a portion of one of the parts of the table and showing a brace connected thereto.

Referring to the figures by characters of reference 1 designates the back wall of the camping kit and on this back wall is arranged a receptacle 2 adapted for holding folding camp stools or the like. The bottom 50 3 of the housing forming the body of the kit connects the lower ends of the side walls 4 and these side walls preferably taper upwardly and are connected at the top by a

top board 5 to which a handle 6 may be connected. Eyes or loops 7 can be provided on the sides of the top board 5 for the reception of straps or the like employed for fastening the kit on the running board of an automobile, the kit, when thus positioned, being arranged with its back wall 1 nearest the automobile body. A hinged partition 8 is preferably connected to the back wall and divides the interior of the kit into an upper compartment 9 and a lower compartment 10. The front of the lower compartment is closed by a fixed wall 11 but the upper compartment 9 is adapted to be closed 60 in front by a combined door and table of novel construction. This closure includes a main or intermediate leaf 12 extending throughout the width of the kit and throughout the height of the compartment 70 9, said leaf being attached to the wall 11 by 75 hinges 13. A hasp 14 may be connected to the upper or free end of this leaf at each corner thereof and is designed to engage one of a pair of eyes 25 so that when padlocks 80 26 are extended through the eyes 25 the leaf 12 will be fastened in closed position.

Hingedly connected to each side of the leaf 12 are extension leaves or wings 15 adapted to fold onto the top or inner face 85 of the leaf 12 and to be supported within the compartment 9 when the kit is closed.

Brackets 16 are secured to the lower portion of the wall 11 at the sides thereof and are adapted to be engaged detachably by 90 the offset ends 17 of braces 18. The other ends of the braces can be forked as shown at 19 so as to straddle the hasps 14 and each brace may be provided at an intermediate point with a socket 20. Balls 21 are seated in these sockets, these balls being located at the lower ends of supplemental braces 22 which are engaged detachably within socket members 23 secured to the leaves 15. Thus it will be seen that when the parts are assembled as shown in Figures 1 and 2 the leaves 12 and 15 will be supported rigidly in front of the body portion or housing of the kit and can be used as a table. When the kit is on the running board of a vehicle 105 this table will be at about the proper height to permit persons seated therearound to eat therefrom.

The compartment 9 can be subdivided by shelves and partitions as illustrated at 24 so 110 as to provide separate spaces for holding cutlery, dishes, a thermos bottle and the like.

The compartment 10 to which access is had by lifting the hinged shelf or partition 8, is intended to hold foodstuffs, a bread box, cooking utensils, etc.

5. When the kit is not in use the braces 18 and 22 can be detached and stored within the cabinet or within the receptacle 2 after which the wings 15 can be folded onto the wing 12 and said wing 12 closed and secured

10 in the manner hereinbefore pointed out.

The entire structure can be carried readily by means of the handle 6 and will not occupy an objectionable amount of room on the running board or extend to an objectionable height.

15. What is claimed is:—

1. A device of the class described including a housing, a receptacle upon the back of the housing, upper and lower compartments within the housing, a hinged partition separating the compartments and constituting the closure of the lower compartment, folding leaves constituting the door of the upper compartment, said leaves being shiftable when the door is open to form a table, supporting braces detachably engaging the housing and one of the leaves, and means carried by the braces for detachably engaging and supporting the other leaves, thereby 25 to hold the leaves extended for use as a table.

2. A device of the class described including a housing, a hinged partition therein

dividing the housing into upper and lower compartments and constituting the closure 35 of the lower compartment, a leaf hingedly connected to the housing and constituting the door of the other compartment, said leaf being movable outwardly and downwardly to form a table, extension leaves connected 40 to and movable with the first named leaf, supporting braces for detachably engaging the housing and the first named leaf, and supplemental supporting braces engaging the extension leaves.

3. A device of the class described including a housing adapted to be secured on the running board of an automobile, a receptacle on the outer surface of the back of the housing; a hinged partition within the housing dividing the same into an upper and a lower compartment, a leaf hingedly connected to the housing and constituting the door of the upper compartment, extension leaves foldable upon the first named leaf, detachably supporting braces for holding all of the leaves extended horizontally from the housing for use as a table, and a handle secured to the top of the housing.

In testimony that I claim the foregoing 60 as my own, I have hereto affixed my signature in the presence of two witnesses.

LOREN W. RAY ANDRIST.
